No. 621,641.

Patented Mar. 21, 1899.

E. ENGSTFELD.

CHENILLE.

(Application filed Apr. 8, 1898.)

(Specimens.)

UNITED STATES PATENT OFFICE.

ERNST ENGSTFELD, OF PHILADELPHIA, PENNSYLVANIA, ASSIGNOR TO THE HENSEL SILK MANUFACTURING COMPANY, OF SAME PLACE.

CHENILLE.

SPECIFICATION forming part of Letters Patent No. 621,641, dated March 21, 1899.

Application filed April 8, 1898. Serial No. 676,911. (Specimens.)

To all whom it may concern:

Be it known that I, ERNST ENGSTFELD, a subject of the Emperor of Germany, and a resident of Philadelphia, Pennsylvania, have 5 invented certain Improvements in Chenille, of which the following is a specification.

One object of my invention is to produce a woven chenille having a heavy central incased or inclosed core from which the chenille yarns 10 project, a further object being to provide such a core with a chenille in which uncut loops alternate with a cut fur, and a still further object being to provide uncut loops of one 15 color or shade and a cut fur of another color or shade. These objects I attain in the manner hereinafter set forth, reference being had to the accompanying drawings, in which—

Figure 1 represents a piece of my improved chenille, showing the same partly untwisted. 20 Fig. 2 represents a piece of the web from which said chenille is made. Fig. 3 is a diagram illustrating the method of weaving said web, and Figs. 4, 5, and 6 are similar diagrams illustrating modifications of my invention. 25

The improved chenille fabric shown in Fig. 1 consists of a central heavy incased or inclosed core 1, from which project uncut chenille loops 2 and a cut chenille fur 3, which 30 in the twisted chenille form spiral convolutions, with the uncut loops and the cut fur lying side by side, the core 1 being exposed between the convolutions when the chenille is not tightly twisted. In producing chenille 35 of this character I preferably employ two bunches of heavy core-strands 4, separated from each other in the loom to the desired extent and each flanked by sets of fine warps 5, the loom being also provided with selvage 40 wires or warps 6, as shown in Fig. 3.

When it is desired that the uncut loops of the chenille shall be of a color or shade different from the cut fur or pile, I use three sets of wefts 7, 9, and 10. The wefts 7 are 45 shot back and forth between and around the bunches of core-threads 4, so as to be wrapped first around one of these bunches and then around the other and are interwoven with the inner sets of fine warps 5. The wefts 9 and

10 are each shot between and around one of 50 the bunches of core-strands and one of the selvage wires or warps 6, so as to pass alternately around the same, and these wefts are interwoven with and bound by the outer sets of fine warps 5, as will be fully understood 55 on reference to Fig. 3, the result being the production of a web such as shown in Fig. 2, which is then divided on the central longitudinal line *xx*, so as to produce two webs, each with a central core inclosed or incased by the 60 weft-yarns and having on one side projecting uncut loops 2 and on the other side a projecting cut fur or pile 3, which when the chenille is twisted will produce the effect shown in Fig. 1. 65

If desired, more than two sets of chenille-wefts may project from the central inclosed or incased core of the chenille by simply increasing the number of wefts employed in the weaving, and by employing a multiplicity of 70 selvage-warps the projecting chenille yarns may form a pattern instead of presenting plain straight edges, as shown.

Where it is not desired that the uncut loops shall be of a different color or shade from the cut fur or pile, only two sets of wefts 11 and 12 may be employed, as shown in Fig. 4, each weft being shot from a selvage warp or wire across the adjoining bunch of core-strands 4 and around the farther bunch, so that each 75 weft will be bound on each side of the bunch of core-strands which it crosses and on the inner side of the bunch of core-strands around which it passes. 80

A still simpler method of weaving the chenille is that represented in Fig. 5, in which but a single weft 13 is employed, this weft being shot across from one selvage warp or wire to the other, so as to pass around the same alternately and crossing both bunches 85 of core-strands in its passage, but being tied down on each side of each bunch of core-strands by the fine wefts 5. 90

In Fig. 6 I have shown still another method of weaving my improved chenille, this method dispensing with the warps 5, the chenille-weft being interwoven with the core-strands 4, so as to be retained thereby, and said core- 95

strands being incased or inclosed by a separate weft 15, which is wrapped around the same in the manner shown.

Having thus described my invention, I claim and desire to secure by Letters Patent—

1. A woven chenille having a core and strands which pass under and over said core and by contact with each other throughout the length of the chenille completely inclose or incase said core, projecting portions of inclosing strands forming a chenille-pile, substantially as specified.

2. A woven chenille having a core, and strands which pass under and over said core and by contact with each other throughout the length of the chenille completely inclose or incase said core, projecting portions of in-

closing strands being interwoven with fine warp on each side of the core, and forming the chenille-pile, substantially as specified. 20

3. A woven chenille having a core, and strands which inclose or incase said core and project from the same on each side to form the chenille-pile, the strands on one side of the core forming loops and those on the other side having cut ends, substantially as specified. 25

In testimony whereof I have signed my name to this specification in the presence of two subscribing witnesses.

ERNST ENGSTFELD.
